COMBINED WEED CUTTER, WEEDEER FORK AND BASKET REMOVER HOOK

Harry H. Jahncke, Webster City, Iowa

Application January 16, 1958, Serial No. 49,270

Term of patent 14 years

(Cl. D35—2)

Fig. 1

Fig. 3

Fig. 1 is a top perspective view of a combined weed cutter, weeder fork and basket remover hook showing my new design;

Fig. 2 is a top plan view thereof on an enlarged scale; and

Fig. 3 is a bottom plan view of Fig. 2.

In Figs. 2 and 3 a portion of the handle has been broken away for convenience of illustration.

I claim:

The ornamental design for a combined weed cutter, weeder fork and basket remover hook, as shown.
